UNITED STATES PATENT OFFICE

MARTHE R. LEMERCIER STROCKER, OF WASHINGTON, DISTRICT OF COLUMBIA

BRASSIÈRE CORSET

Application filed October 25, 1929. Serial No. 402,395.

My invention relates to a brassière corset which will hold the figure of the wearer in a graceful, firm, and slender outline, which will support the bust, waist, hips and abdomen with a minimum of restraint, and stiffness, one which will follow every move of the figure, and yet restrain it in a graceful outline, without bunching or ridges at any place.

To accomplish the above, the objects of 10 my invention are:

To provide a corset with stays that break at the natural places of movement of the body, at the waist, hips and back, and that yet hold the middle trunk in a pleasing outline; 15 to provide a firm bust support that will not give or stretch at the front or sides; to provide a very low back for the corset, extending nearly to the waist line, along with this firm bust support; to provide an inside waist 20 band that will not stretch, but which will both hold the waist firm and allow the greatest freedom of movement and comfort, and allow the corset to keep a straight outline; to provide a firm abdominal support, and hip 25 support, and to so attach the lower side part of the garment to the back and front of the garment as to allow for freedom of movement around the hips, and ease in sitting down.

30 Other objects and advantages of my invention will more particularly appear from the following description and accompanying drawings, in which:

Figure 1 is a perspective view of the front 35 and right side of my new corset. Fig. 2 is a perspective view of the back and left side thereof. Fig. 3 is a view similar to Fig. 1, with the garment partly unfastened. Fig. 4 is a view of the inside of the garment, the 40 garment being opened out flat.

In the drawings similar numerals refer to similar parts throughout the several views.

The garment is designed to extend low, around the hips of the wearer, and is composed of an inner front gore, 1, an outer front gore, 9, side gores 2, 3, 7 and 8, and back gores 45 4, 5 and 6.

Front gores 1 and 9 have corresponding insets of elastic material 10 and 11 at their 50 lower edges to permit greater ease to the

wearer in sitting down. Inner front gore 1 has hooks 12, fastening in eyes 13, under a strip of soft material 14, on the side of the garment next to gore 9. These hooks and eyes form a positive joining means, and the 55 strip 14 prevents their contact with the body of the wearer.

Front gore 1 extends above the bust line, to positively support the wearer, and it extends snugly around the abdomen, to support that 60 part of the body. It further has stays 15 therein extending from a little above the waist to the hip line to further support the abdomen and to prevent ridging when the wearer sits down, but to allow ease of movement at the same time. A section of belt likewise extends across this member and gores 4 and 6 to give added strength around the waist, and to prevent stretching of the 65 garment.

Front gore 9 is a little larger than front gore 1, to smoothly cover gore 1, but not to bear the same strain as gore 1, and it therefore retains its smoothness. It fastens over 70 gore 1 with snap fasteners, 16 and 17, one element of which 16 are on gore 9, as in Fig. 4, and the other element of which 17, are on the far side of gore 1, as in Fig. 3. Gore 9 has an intermediate lace or porous section, 18, of considerable strength, to further support the bust, and an upper, thinner, 75 lace or porous section, 19, to cover the wearer, and which is quite porous, for coolness.

Side brassière sections 20, are likewise of 80 strong lace or porous material to hold the upper, or brassière, sections of gore 1 and lace section 18 above gore 9. The warp of the weave of these sections 20 is parallel to the upper edge of the sections as at 35, so that they will stretch as little as possible, and 85 therefore, positively support the bust. Across these sections 20, are very soft stays, 21, substantially perpendicular to the upper edge of the sections, but diagonal to the wearer. These stays not only support the 90 wearer, but also sections 20, so that these sections may always remain smooth, and not break with the bending of the body.

Gores 2 and 3 and 7 and 8 are respectively 95 sewed together at their inner edges, and they 100

there enclose stays, 22, which run from the waist line to the hip line, thus firmly supporting the middle trunk and allowing absolute freedom of movement. The warp of the 5 weave of these gores 2, 3, 7 and 8 is parallel to the waist line as at 36, to as nearly as possible prevent stretching of the side gores. Above these side gores, and below sections 10 20, are sections 23, of the regular corset material, as are also all the gores except 5, and the warp of the weave of these sections 23 is also parallel to the waist line as at 37, to further prevent stretching.

To further prevent stretching at the sides, 15 and to keep a smooth side outline, inside side belts 24, of fair width, are placed at the waist line, and in these belts are stays 25, substantially parallel to stays 21, and some of which overlap stays 21 and stays 22. These separate overlapping stays both support firmly 20 and allow freedom of movement. These belts are sewed to the corset only at their ends, in order not to disturb the lines of the corset proper.

25 To each side of the side sections, elastic shoulder straps 26, 26 are fast, to hold the garment up on the wearer.

Between gores 1 and 2 and 9 and 8 are short stays, 27, beginning at the waist line 30 and stopping at the hip line. Likewise between gores 3 and 4 and 6 and 7 are stays, 28, extending from the top of the garment to the hip line, these stays recover the shape due to breaking adjacent stays 29 at the waist 35 line, as described below.

In back gores 4 and 6 are stays 29, 29, extending from the hip line to the top of the garment, and which are broken at the waist line, as at 30, to allow freedom of movement. 40 The garment has a very low back, so the upper parts of stays 29 are quite short. In the back center of the garment, a gore of elastic 5, is inserted, for comfort and to allow for some expansion of the garment. This gore extends the length of the garment. Around the 45 top of the sides and back of the garment, a smooth edging 31 passes, to give a smooth, finished upper edge to the garment.

Below gores 2, 3, 7 and 8, are elastic sections 32, surrounding the hips of the wearer. These sections have darts 33 therein, serving to mold the wearer's hips, which do not extend to the bottom of the sections, and therefore do not weaken the bottom of the sections. The sections are cut on an irregular line at the top, in order not to have the gores 55 2, 3, 7 and 8, form a binding or cutting line around the wearer, and these sections join the side gores at the front gores low, so that 60 the side gores may serve positively to support the abdomen, and they join the side gores at the back gores high, to allow greater freedom of movement. The elastic side sections are shallow in front and deep in back, 65 and the adjoining front and back gores are

correspondingly short and long to allow the wearer freedom in sitting down.

The bottom of the garment has thereon a flounce 34, of lace or other material and garters 35.

70 Thus the wearer may be held evenly and comfortably, and have the desired support along with the minimum of restraint in either feeling or movement, also the outline of the figure of the wearer is always smooth and 75 straight.

Depending on the size of the garment, more, or fewer, gores and stays could be used, and many changes could be made in the construction and arrangement of the parts without departing from the spirit and scope of the invention or sacrificing its material advantages, the form hereinbefore described being merely a preferred embodiment thereof, and I contemplate the employment of any 80 devices that are within the scope of the appended claims.

I claim:

1. In a brassière corset, a corset portion comprising, a front gore, a plurality of side and back gores, a front porous brassière section above said front gore, said back gores terminating, at the top, just above the waist line, side porous brassière sections attached to said front brassière section and the top edges of which slope down to, and are attached to said back gores, the warp of the 90 weave of said side brassière sections being parallel to the top edges of said sections.

2. In a brassière corset, a corset portion comprising, a front gore, a plurality of side and back gores, a front brassière section above said front gore, said back gores terminating, at the top, just above the waist line, side brassière sections attached to said front brassière section and the top of which slope down to and are attached to said back gores, stays in said side brassière sections substantially perpendicular to the upper edges thereof, side belts attached to said front and back 100 gores at the waist line, a plurality of stays 105 therein substantially parallel to said first named stays, and stays in said side gores extending from the waist line to the hip line, said last named stays being overlapped by 110 said side belt stays.

3. In a corset, a front gore, a plurality of back and inelastic side gores, said front gore and said back gores extending well over the lower trunk of the wearer, elastic side sections being connected across their width at their upper edges to said side sections, gores well below the waist line, and being connected to said front gore and said back gores, to the front gore well below the hip line and to the back gores well above the hip line, a downwardly pointed dart being in the upper part only of said elastic side sections to insure a snug fit around the hips of the wearer, and to maintain a strong lower elastic edge.

4. In a brassière corset, a plurality of side and back gores, an inner inelastic and an outer front gore, the former fastening to the inside edge of the latter and the latter overlapping and fastening to the outside edge of the former, said inner front gore extending above the bust line and said outer front gore have above it, a porous brassière portion.
5. In a corset, a front gore, a plurality of back and inelastic side gores, said front gore and said back gores extending well over the lower trunk of the wearer, said side gores extending well below the waist line and being there connected at their lower edge across their width to elastic side sections which are also connected to said front gore and said back gores, to the front gore well below the hip line and to the back gores well above the hip line, to both support the abdomen and give flexibility of movement to the wearer, said elastic side sections being shallow in front and deep in back.
6. In a brassière corset, a corset portion comprising, a front gore, a plurality of side and back gores, a front brassière section above said front gore, side brassière sections attached to said front brassière section and said back gores, stays in said side gores beginning at and extending from the waist line to the hip line, side belts free from said side gores intermediate their ends and at their ends attached to said front and back gores at the waist line, a plurality of diagonally placed stays in said side belts overlapping said first named stays.
7. In a brassière corset, a corset portion comprising, inelastic front and back gores, circumferentially, substantially unstretchable side gores directly connecting said front and back gores and extending well below the waist line, a front porous brassière section above said front gore, inelastic side porous brassière sections attached to said front brassière section and said back gores, and said back gores having a central elastic gore therebetween, and extending the length of the garment.
